DESIGN FOR A TAFFRAIL LOG SPINNER

Charles Ellis Ellicott, Jr., Baltimore, Md.

Application February 15, 1938, Serial No. 75,156

Term of patent 7 years

To all whom it may concern:

Be it known that I, Charles Ellis Ellicott, Jr., a citizen of the United States and a resident of the city of Baltimore, State of Maryland, have invented a new, original, and ornamental Design for a Taffrail Log Spinner, of which the following is a specification, reference being had to the accompanying drawing, forming a part thereof.

Figure 1 is a side view of the taffrail log spinner showing my design; and

Figure 2 is a similar view of the device rotated 90°.

I claim:

The ornamental design for a taffrail log spinner substantially as shown.
